UNITED STATES PATENT OFFICE.

JAMES FEAGINS, OF FRISCO, TEXAS.

COTTON THINNER.

Application filed June 19, 1924. Serial No. 720,932.

To all whom it may concern:

Be it known that I, JAMES FEAGINS, a citizen of the United States, residing at Frisco, in the county of Collin and State of Texas, have invented certain new and useful Improvements in Cotton Thinner, of which the following is a specification.

This invention relates to agricultural implements and refers more particularly to new and novel improvements in weeding, cultivating and spacing implements for farm vegetation, preferably cotton.

The primary object of this present invention is to provide a simple and durable machine of this character, also with a view of economy, which will effectually produce, as near as possible, the same result as is produced by chopping or weeding the vegetation by hand, or perhaps a better result may be obtained due to the acreage that may be covered in a shorter space of time.

Another object of the invention lies in the construction and arrangement of the lever mechanism which controls the foot beams.

Other features and advantages contained in the new and improved agricultural implement, as well as those above set forth, will be pointed out and described in the course of the following description, in which the drawings attached hereto represent a preferred form of the invention and wherein:

Figure 1 represents a side elevational view of the invention.

Figure 2 shows a top plan view of the invention.

Figure 3 is a detail view, partly in section, showing the manner in which the wheels of the device are secured to the main body.

Using similar reference characters to point out the various working principles of the invention, 1 denotes an angle iron extending the full length of the machine. Upon either end of this angle iron is bradded, bolted or otherwise suitably secured, a short substantial axle 2, which is aided in its rigidity in relation to the angle iron 1, by a block 3. Two wheels of ordinary construction with moderately curved peripheries are indicated by the numeral 3^a.

It will be noted by reference to Figure 2 of the drawings that the machine is provided with a cross bar 5, having its ends twisted at right angles to the central portion of the bar. This is obviously for the

purpose of applying strength and rigidity to the bar. The flat surface of the ends of the bar 5 are turned in and securely bolted to the angle iron 1.

A series of foot beams 6-6 are bolted to the angle iron 1 and are suspended from the cross bar 5 by means of U bolts 7-7. It will be observed that these beams are also curved at right angles in the same manner as the cross bar 5. The angle iron 1 is provided with a series of extra adjusting holes 4-4 in order to provide for the spacing of the foot beams 6-6.

Secured to the angle iron 1 and spaced apart are a pair of clevises 11-11 which provide a fulcrum for the U shaped member 12. These members hinge upon a bar 13.

Extending across this U shaped member 12 is another small angle iron 14 to which the tongue 14^a is secured, the latter also being secured to the foremost portion of the U shaped member 12 at points 15. A flat metal bar is also secured to the small angle iron 14 carrying upon its end a clevis 16^a which is adapted to receive a double tree 17. A seat 18 is situated upon the flat bar 16.

Extending upwardly from the angle iron 1 is an upright member 18^a. This member is stationary to the said angle iron 1. At the uppermost end of this member is pivotally secured a lifting bar 19, the lower end of which is rigidly secured to the cross-bar 5. Also pivotally secured to the top of the upright member 18^a is a double bar 19^a which is slightly turned at point a, and at this point a lever 20 is adapted to be interposed between the two bars constituting the bar 19^a, and pivoted at point b. The lever then extends downward and is again pivoted to the member 21. It will be noted that the bar 19^a is provided with a movement limiting bolt 22.

The present invention is adapted to be used in plowing vegetation in a crosswise manner to obtain the best results and it will be understood that any desired number of beams may be used and that minor changes in the arrangement and construction of the invention may be made without departing from the spirit of the invention and in keeping with the following claim:

A cotton thinner comprising an angle bar, blocks secured within the opposite ends of said bar, a stub shaft carried by each block, supporting wheels carried by said shafts, plow

beams, means for adjustably connecting the upper ends of said beams to said angle bar, a cross bar having its opposite ends connected to said angle bar and extending rearwardly thereof, **U**-bolts for connecting said cross bar to said beams, a **U**-shaped member hingedly connected to and extending forwardly of said angle bar, an upright member connected to said angle bar, a lifting bar

connecting said upright member to said cross bar, a double bar having one end connected to said lifting bar, a lever pivotally mounted upon said **U**-shaped member, and means for connecting said lever to said double bar.

In testimony whereof I have signed my name to this specification.

JAMES FEAGINS.
